UNITED STATES PATENT OFFICE.

WILLIAM J. RYAN, OF PHILADELPHIA, PENNSYLVANIA.

DESIGN FOR A HAT-PIN TIP.

SPECIFICATION forming part of Design No. 33,158, dated September 4, 1900.

Application filed November 13, 1899. Serial No. 736,886. Term of patent 7 years.

To all whom it may concern:

Be it known that I, WILLIAM J. RYAN, a citizen of the United States, residing at Philadelphia, county of Philadelphia, and State of Pennsylvania, have invented and produced a new and original Design for Hat-Pin Tips, of which the following is a specification, reference being had to the accompanying drawings, forming a part thereof.

1c Figure 1 is a side view of a hat-pin tip, showing my new design. Fig. 2 is an end view thereof.

15 As shown in the drawings, the leading or material feature of my design consists of a tapering body A, having a circular scroll B

formed thereon, and a faceted head C, which forms the top of the ornament. A tapering socket D is formed in the inner end of the body.

Having thus fully described my invention, what I claim as new is—

The design for a hat-pin tip as herein shown and described.

In testimony whereof I have hereunto affixed my signature in the presence of two subscribing witnesses.

WILLIAM J. RYAN.

Witnesses:

MARY E. HAMER,
L. W. MORRISON.
